UNITED STATES PATENT OFFICE

106,181

DESIGN FOR A COMMUNICATIONS UNIT CABINET

Stuart J. Cardoza, Berkeley, Calif., assignor to
Lake Manufacturing Company, Oakland,
Calif., a corporation of California

Application May 8, 1937, Serial No. 69,226

Term of patent 7 years

To all whom it may concern:

Be it known that I, Stuart J. Cardoza, a citizen of the United States, residing at Berkeley, in the county of Alameda and State of California, have invented a new, original, and ornamental Design for Communications Unit Cabinets, of which the following is a specification, reference being had to the accompanying drawing, forming part thereof.

Fig. 1 is a perspective view of the communications unit cabinet, showing my new design;

Fig. 2 is a front elevational view;

Fig. 3 is a side elevational view; and
Fig. 4 is an elevational view of the bottom or base.

The cabinet is adapted to receive whatever type of communications unit may be desired, such as, for example, a speaker, a radio receiving set, an inter-office wired announcer, etc.

I claim:

The ornamental design for a communications unit cabinet substantially as shown and described.

STUART J. CARDOZA.
